UNITED STATES PATENT OFFICE.

DANIEL A. DRAPER, OF EAST CAMBRIDGE, MASSACHUSETTS.

IMPROVEMENT IN SPRING-CATCHES FOR LAMPS.

Specification forming part of Letters Patent No. 39,131, dated July 7, 1863.

To all whom it may concern:

Be it known that I, DANIEL A. DRAPER, a resident of East Cambridge, in the county of Middlesex and State of Massachusetts, have invented a new and useful improvement in spring-catches for the chimney and deflector-holders of lamp-burners; and I do hereby declare the same to be fully described in the following specification, and represented in the accompanying drawings, of which—

Figure 1 is a vertical section of a lamp-burner with my improvement. Fig. 2 is a front, and Fig. 3 an edge, elevation, of the spring-catch thereof.

My invention or improvement rests in the peculiar spring-catch and its application to or arrangement with the cap or deflector holder and the wick-tube.

In the drawings, A is the deflector, supporter, or holder, while B is the conical deflector and C the wick-tube, of an ordinary burner of a lamp for the combustion of kerosene or other hydrocarbon.

The spring-catch for aiding in confining the deflector and the glass chimney in place within the cap or holder A is shown at D. It consists of a thin strip of metal bent substantially in the form represented in Fig. 3, in order that when in place in the lamp cap or burner, its lower part, a, may rest directly against one side of the wick-tube, the part which may be alongside of the said tube being tapered or made thin, so as to act as a spring.

As shown in the drawings, the strip of metal composing the catch D has four flexures, b c d e, and at a short distance below the second flexure, e, it is furnished with two ears, ff, extending from its two opposite edges, as shown in Figs. 2 and 3.

In the application of the catch to the lamp-cap or deflector-holder the upper part of the catch, or that part of it which is above the two

ears ff, is made to extend through a slot or hole, g, formed laterally through the rim of the said holder, the two ears ff bearing against the rim adjacent to each end of the slot. Under these circumstances the lower portion of the catch, or the part extending below the lowermost flexure, e, is to rest at its lower part directly against the adjacent side of the wick-tube, which constitutes a bearing for it. The lower part of the spring-catch is provided with one or two stops or shoulders, h, to arrest the upward motion of the spring during its retraction. In accomplishing this result the shoulder or shoulders are to come in contact with the lamp-cap, or that part of it immediately adjacent to each end of the slot i, through which the spring part of the catch extends. The flexure b by means of the spring will be pressed down on the deflector or the chimney when on the deflector, and will thus operate to keep the deflector or it and the chimney in place in the holder. By a person applying his thumb to the upper part of the spring-catch and pressing it back, the catch may be turned or moved so as to liberate the chimney and deflector, or the latter, in a manner to enable such to be readily removed from the holder.

The advantage of my spring-catch is its simplicity in make and application, it requiring no direct connection by solder or otherwise with the wick-tube or the cap, it being held in place by its flexures and projections.

I claim—

The construction of the spring-catch and its application or arrangement relatively to the deflector-holder and the wick-tube, the whole being substantially as above specified.

DANIEL A. DRAPER.
